UNITED STATES PATENT OFFICE.

ALBERT RONTKE, OF BRIDGEPORT, CONNECTICUT, ASSIGNOR TO THE SINGER MANUFACTURING COMPANY, A CORPORATION OF NEW JERSEY.

THREAD-CUTTING MECHANISM FOR SEWING-MACHINES.

1,156,821.

Specification of Letters Patent.

Patented Oct. 12, 1915.

Application filed August 2, 1912. Serial No. 712,843.

To all whom it may concern:

Be it known that I, ALBERT RONTKE, a citizen of the United States, residing at Bridgeport, in the county of Fairfield and 5 State of Connecticut, have invented certain new and useful Improvements in Thread-Cutting Mechanism for Sewing-Machines, of which the following is a specification, reference being had therein to the accompanying drawings.

This invention relates to improvements in sewing machines for closing the mouths of filled bags, and has for its object to provide improved means for severing the thread between the successive stitching operations, to which end there is provided a cylinder bed sewing machine having its needle-carrying bar arranged to operate in a substantially horizontal plane and provided with a 10 thread-cutter normally located at one side of the vertical plane intersecting the line of seam formation, thus effecting a construction convenient of manipulation and particularly adapted to meet the requirements 15 of closing the ends of comparatively small sized packages.

In the accompanying drawings illustrating the invention, in the several figures of which like parts are similarly designated, 20 Figure 1 is a rear side view of a sewing machine together with the improved thread-cutting mechanism shown as attached to the cylinder bed-plate, the machine being arranged to cause the needle-bar to be actuated in a substantially horizontal plane. Fig. 2 is an end view of the cylinder bed-plate and thread-cutting mechanism, together with a portion of the presser-foot. Fig. 3 is a front side view of a portion of 25 the cylinder bed-plate and thread-cutting mechanism, together with dotted line views of a stitched bag and a partially stitched bag. Fig. 4 is a detail view of the thread-cutting mechanism. Fig. 5 is a detail view 45 of the shear blades.

The invention is shown as applied to a Singer 54 class machine, but as it relates only to the construction and application of the thread-cutting mechanism, only such reference will be made to the other elements of the machine as is deemed necessary for a proper understanding of its application.

Referring to the figures, 1 represents the sewing machine base, 2 the bracket arm, 3 50 the cylinder bed-plate, 4 the hand or band

wheel carried by one form of looper-actuating shaft (not shown), 5 the needle-carrying bar, 6 the cloth-presser-carrying bar provided with the cloth-presser 7, 8 the needle, 9 the throat or needle plate, 10 the feed-dog, 15 and 11 the upper portion of a vertically arranged standard, to which the sewing machine is secured by nut bolts, as 12.

13 represents the cutter base-plate secured by screws, as 14, to the cylinder bed-plate, 18 15 a bell crank operating lever which is provided with an integrally formed hub 16 and pivotally mounted on said cutter base-plate by a stud screw 17 threaded into said plate.

18 and 19 represent coacting shear blades 20 constructed with guide arms 20 and 21 each arranged at an angle to its respective shear blade, said blades being pivotally mounted on a nut bolt 22 carried by the arm 23 of the operating lever 15 and yieldingly held 25 in cutting relationship by spring 24 surrounding the nut bolt 22, which latter is free to be moved in the direction of its length in the hub 16'. The free end of the arm 25 of said bell crank operating lever is 30 connected with common means to advance the shear blades into position to sever the thread, as shown in Fig. 4, a spring 26 secured at one end to said bell crank lever and having its opposite end secured to the cylinder bed-plate acting to hold said cutting 35 blades in their normal positions, as shown in Figs. 1, 2 and 3.

Each of the guide arms 20 and 21 is provided with a guiding element or pin, as 27, 40 which tracks one of the openings 28 formed in the cutter base-plate 13 which, in connection with the swinging movement of the pivotal point comprising the nut bolt 22, effects the shearing action of the blades and 45 their movements into and out of cutting relationship with the sewing thread.

Claims:

1. In a sewing machine, the combination with a bed-plate, of a thread-cutting mechanism normally located at one side of the line of seam formation, said cutting mechanism comprising a cutter-actuating lever provided with pivotally attached cutting blades resiliently held in cutting relationship and movable across the line of seam formation, each of said blades being provided with a guide arm, of stationary guiding elements in effective relation with said guide arms to impart shearing movements 105
2. In a sewing machine, the combination with a bed-plate, of a thread-cutting mechanism normally located at one side of the line of seam formation, said cutting mechanism comprising a cutter-actuating lever provided with pivotally attached cutting blades resiliently held in cutting relationship and movable across the line of seam formation, each of said blades being provided with a guide arm, of stationary guiding elements in effective relation with said guide arms to impart shearing movements 110

to said blades as the latter are moved across the line of seam formation.

2. In a sewing machine, the combination with a bed-plate, of a thread-cutting mechanism normally located at one side of the line of seam formation, said cutting mechanism comprising a cutter base-plate secured to said bed-plate, a cutter-actuating lever pivotally mounted on said base-plate and provided with pivotally attached cutting blades resiliently held in cutting relationship, each of said blades being provided with a guide

arm in effective relationship with said base-plate to impart shearing movements to said blades as the latter are moved across the line of seam formation.

In testimony whereof, I have signed my name to this specification, in the presence of two subscribing witnesses.

ALBERT RONTKE.
